Dec. 19

Henry G. Thompson, New York, New York.
Letters Patent No. 19, dated April 4th 1844.

The Schedule referred to in these Letters Patent and making part of the same. —

To all whom it may Concern. —

Be it known that I, Henry G. Thompson of the City of New York have invented or designed a new pattern or combination of Figures to be worked into Ingrain Carpeting, and I do hereby declare that the following is a full and exact description and to enable others skilled in the art to make and use my design — I describe the construction as under. —

A Comber, super ingrain Carpet design drawn so to be worked in various colours but more especially in Ruby ground, with the two set figures worked in shot about yellow & white ground or green and white ground and the flowers chintzed with red or any other colour. The main feature of this design is that the warps of each figure do not interfere with one another — For instance, the yellow warp being on the right hand side of the Carpet, and serving to bind the filling of the yellow and white set figures, and the red warp on the left hand side serving to bind the filling of the red flower, and green warp serving to bind the filling of the green leaves. I distinguish this design from the common run of ingrain patterns usually worked on the Jacquard Loom in the shading of the figures to be worked up as much by the Warp as filling. —

What I claim as my invention is the peculiar combinations of Figures above described being different from any thing ever wrought before in ingrain Carpeting.
